UNITED STATES PATENT OFFICE

GEORGE H. MERRICK, OF ST. LOUIS COUNTY, MISSOURI

WATER MOTOR

Application filed April 20, 1927. Serial No. 185,333.

This invention relates to an improvement in water motors and has for its primary object the purpose of providing a motor which can be operated in naturally flowing streams 5 or rivers.

Another object of the invention is in providing an improved water motor with buoyant supporting means so that the motor and supporting means therefor can float in the 10 stream or river.

A further object of the invention is in providing an improved water motor having pontoons or buckets which will be traveled longitudinally down stream for a given distance 15 by the water current before they are returned up stream to again engage the water current.

Other and further objects will appear in the specification and be specifically pointed out in the appended claims, reference being 20 had to the accompanying drawings, exemplifying the invention, and in which:—

Figure 1 is a longitudinal section taken through this improved water motor.

Figure 2 is a vertical transverse section 25 taken approximately on the line II—II of Fig. 1.

Figure 3 is a perspective view of one of the propelling paddles.

Figure 4 is a fragmentary plan view of 30 the forward end of the supporting pontoons of the motor.

Referring by numerals to the accompanying drawings 1 designates a floating deck made from a pair of spaced apart paralleling 35 pontoons 2, said pontoons being held in their spaced apart paralleling positions by the transverse cross members 3 thereby providing a channel or waterway 4^a between the pontoons.

40 Mounted on each pontoon 2 adjacent their forward ends is a bearing 4, said bearings being in alignment and supported by said bearings is a horizontally disposed shaft 5.

Secured to the shaft 5 between the bearings 45 4 are a pair of guiding wheels 6 each having a flange 7 formed on its periphery on one side of the tread thereof.

50 Mounted on each of the pontoons 2 adjacent their rear ends are a pair of alining bearings 8 and horizontally supported in

said bearings is a shaft 9 for the support of a pair of guiding wheels 10 which are rigidly secured thereto between the bearings, each of said wheels having a flange 11 formed on one side of the tread thereof.

The pairs of wheels 6 and 10 depend within the channel 4^a and the wheels on each shaft are spaced equal distances apart and as the channel 4^a is longitudinally disposed each wheel 6 of the shaft 5 will be in longitudinal 55 alignment with a wheel 10 of the shaft 9.

Mounted over each alining pairs of wheels 6 and 10 is an endless chain belt 12, and secured to said belts are a series of transversely spaced supporting rods 13 and swingingly supported on each rod is a propelling paddle 14, each paddle being provided with a pair of bearings 15 through which respective rods 13 are passed for securing the paddles between the belts.

70 Mounted on each pontoon intermediate of the bearings 8 and 4 is a bearing 16 for the support of a horizontally disposed shaft 17, said shaft being located beneath the upper belt stretch 18, and rigidly secured to said shaft are a pair of sprockets 19, each of which is in mesh with a respective chain belt 12.

75 When a motor of this improved character is in support in the river or stream upon the pair of pontoons 2, the water course or channel with respect to the paddles 14 will be through the waterway or channel 4^a formed between the pontoons and the paddles 14 will be propelled in the direction of the arrow in Fig. 1 thereby moving the chain belts 12 and 80 causing them to travel over respective pairs of wheels 6 and 10 and as the belts 12 are traveled the sprockets 19 in mesh with said belts will be turned thereby revolving the shaft 17 which may extend to the shore from 85 where power may be derived from the shaft or the shaft may terminate in the deck 1 and be used to operate a generator.

90 For holding each paddle 14 in vertical position as they are traveled down stream, each paddle is provided with a brace 20 which will bear against the underside of the lower chain stretch 21 and when the paddles reach the return wheels 10 they will be carried upwardly and in which the brace of each paddle 95 100

will leave engagement with the belts 12 as each paddle swings on its respective rod 13 and when each paddle reaches a position on top of the return wheels 10, the paddles themselves will lay on the upper chain belt stretch 18. This manner of permitting the paddles to swing as they travel upwardly around the wheels 10 holds the paddles in approximate vertical position as they are lifted from the stream, the paddles therefore not lifting any water from the stream.

The paddles 14 after traveling the belt stretch 18 and reaching the wheels 6, will be caused to turn over when they each reach approximate positions indicated at A in Fig. 1 and will assume vertically inclining positions as they enter the water, and in consequence the paddles will cut the water as they enter.

20 The flanges 7 and 11 of respective wheels 6 and 10 serve as guiding means to the chain belts 12.

In the use of a motor of this improved water motor in which the paddles 14 are permitted to travel a considerable distance down stream by the force of the current thereagainst, it is obvious therefore that greater power will be derived from the stream or river current and if desired the supporting shafts 5 and 9 can be disposed farther apart so that more paddles can be engaged on the chain length and consequently a more powerful motor can be provided.

This improved motor can be placed in cooperation with a waterfall by omitting the floating deck and providing standards for supporting the shafts 5 and 9 in positions wherein the shaft 5 can be arranged above the shaft 9 so that the device can be inclined or vertically disposed so that the pushing paddles 14 can be engaged in the waterfall.

The device can also be used in a small stream by omitting the floating deck and mounting the standards for supporting the bearings of the shafts 5 and 9 from the banks of the streams.

It is to be noted that the brace work 20 of each paddle is provided with an elongated opening 22, each being for the purpose of preventing the brace work of each paddle to travel against the wind in which the air currents will pass through the apertures 22 and the paddles therefore will prevent less resistance through the air currents when a breeze is blowing down stream.

An improved water motor of this character can be entirely submerged in the river if desired as the paddles 14 will offer a greater resistance to the water during their travel down the stream with the water than they will when they travel up the stream on the upper stretches or chain lengths 18 of the chain belts 12 for the reason that the paddles on their return up stream are projected horizontally against the current.

What I claim is:

1. A water motor comprising two sets of flanged revoluble members, endless belts mounted over said members having a series of spaced paddles swingingly secured thereto, said paddles being maintained on said members by the flanges thereof and adapted to be engaged in a body of flowing water as they are travelled in one direction, and an open brace structure secured to each paddle extending the approximate length thereof, said brace structures by their cooperation with said paddles adapted to maintain said paddles in an approximate vertical position during their travel through the water.

15 2. A water motor comprising a pair of spaced revoluble members, endless belts mounted over said members having a series of spaced paddles swingingly secured thereto, said paddles adapted to be engaged in a body of flowing water as they are travelled in one direction, and a rectangular open brace structure forming a part of each paddle adapted to cooperate with said belts to maintain said paddles in a working position during their travel through the water.
